VERTICAL TAKE-OFF AIRPLANE

John J. Schneider, Springfield, Pa., assignor to Vanguard
Air & Marine Corporation, Malvern, Pa., a corpora-
tion of Pennsylvania

Filed Aug. 21, 1961, Ser. No. 66,437

Term of patent 7 years

(Cl. D71—1)

Fig. 1

Fig. 2

*Fig. 3**Fig. 4*

FIG. 1 is a perspective view of a vertical take-off airplane showing my new design;

FIG. 2 is a front elevational thereof;

FIG. 3 is a top plan view of the airplane; and

FIG. 4 is a side elevation thereof, the opposite side being substantially the same in appearance aside from the door as indicated in FIG. 3.

I claim:

The ornamental design for a vertical take-off airplane, as shown and described.
